United States Patent Office

Des. 191,323
Patented Sept. 12, 1961

191,323

BREAD TRAY

William Wistar Robinson, Forest Hills, N.Y., assignor to Arnold Bakers, Inc., Port Chester, N.Y., a corporation of New York

Filed Nov. 29, 1960, Ser. No. 63,018

Term of patent 3½ years

(Cl. D44—10)

FIG. 1

FIG. 2

FIG. 1 is a top plan view of a bread tray, showing my new design; and

FIG. 2 is a perspective view of the bread tray.

The essential features of the design are shown in full lines.

The outer surface of the tray is unornamented.

I claim:

The ornamental design for a bread tray, as shown and described.
